UNITED STATES PATENT OFFICE.

JOHN F. O'CONNOR, OF CHICAGO, ILLINOIS, ASSIGNOR TO WILLIAM H. MINER, OF CHAZY,
NEW YORK.

MECHANISM FOR RECORDING ACTIONS OF DRAFT-GEAR.

1,303,948.

Specification of Letters Patent.

Patented May 20, 1919.

Application filed September 5, 1916. Serial No. 118,412.

To all whom it may concern:

Be it known that I, JOHN F. O'CONNOR, a citizen of the United States, residing at Chicago, in the county of Cook and State of Illinois, have invented a certain new and useful Improvement in Mechanism for Recording Actions of Draft-Gears, of which the following is a full, clear, concise, and exact description, reference being had to the accompanying drawings, forming a part of this specification.

This invention relates to improvements in mechanism for recording actions of draft gears.

One object of the invention is to provide an arrangement for recording the actions of draft riggings of railway cars, which mechanism is so arranged as to simulate as much as possible, the actual conditions encountered in the operation of draft riggings of cars in service.

Another object of the invention is to provide a mechanism of the character described which is so arranged that variations may be made in the conditions under which the records are made, to thus initiate the different conditions encountered in actual service.

The invention furthermore consists in the improvements in the parts and devices and in the novel combinations of the parts and devices herein shown, described and claimed.

In the drawing forming a part of this specification, Figures 1 and 1^a together constitute a side elevation of a mechanism embodying my invention. Figs. 2 and 2^a together constitute a top plan view of the structure illustrated in Figs. 1 and 1^a except that the cars and portions of the car lifting means are omitted. Fig. 3 is a vertical, transverse section taken on the line 3—3 of Fig. 1 and illustrating more particularly the scales for weighing one of the cars.

Fig. 4 is a longitudinal, vertical section taken substantially centrally of the test cars and illustrating more particularly the draft gears. Fig. 5 is a vertical enlarged sectional view of the means for clutching one end of the test car and for elevating the same. And Fig. 6 is a horizontal sectional view of the structure illustrated in Fig. 5 and taken substantially on the line 6—6 of the latter.

Broadly stated, the improved mechanism embodies a test car supported to swing and adapted to be elevated to different heights

before being released to thereby vary the blows or impacts of the test car on another car, the two cars being provided with draft gears to absorb the blows and having associated recording mechanism for making a record of the action.

In the drawing, A designates a test car of the gondola type, the same being mounted on trucks in usual manner, the axles of the trucks being mounted in journal boxes 10—10, which are turned upside down. Each of the journal boxes is carried at the lower end of a link or heavy rod 11, the latter in turn being each secured at their upper ends to another journal box 12, the journal boxes 12 being mounted on transversely extending axles 13. The axles 13 are mounted in suitable bearings 14 carried by the superstructure of a frame-work or housing within which the various parts of mechanism are located. Said frame-work or housing is preferably built up of commercial plates and has a plurality of posts 15—15, upper horizontal side beams 16—16, transverse beams 17—17 and diagonal bracing angles 18—18, all the plates and angles being suitably connected by gussets. The posts of the frame-work or housing are provided with suitable concrete or other foundations and a pit is also formed, extending longitudinally of the housing at the bottom thereof, as indicated at 19 in Fig. 3. This pit is provided to accommodate platform car scales 20—20, which may be of any suitable or well known form and having a lever 120 from which extends a rod 21, the latter being connected to a balancing beam (not shown). By employing the scales above mentioned, the weight of the car plus any load which may be placed therein can be determined at any time. In practice, the car will preferably be loaded so that the weight of the load and car will approximate 150,000 lbs. Ordinarily, the test car A does not rest on the rails of the scale platform, but means are provided for lowering the car on to the scales in order to obtain the weight, said means comprising turn buckles 22 in each of the supporting rods or links 11; by adjusting the turn buckles 22, it is obvious that the effective lengths of the links 11 can be varied as desired.

From the preceding description, it is apparent that the test car A is so mounted that it may be raised and lowered and always

maintained in a horizontal position. The dotted lines in Figs. 1 and 1^a indicate the position of the test car A when the same has been raised.

- 5 In order to raise the test car A, the same is provided at its inner end with a rigidly attached casting 23. The casting 23 is provided with a pair of spaced slots 24—24 within which are adapted to be received a 10 pair of links 25—25, the latter being pivotally connected to the casting 23 as by means of a heavy pin 26. The links 25, at their free ends, are connected by another heavy pin 27 which is adapted to be gripped by a pair 15 of jaws about to be described. Pivotally mounted upon the super-structure of the frame-work in a similar manner to that of the test car by links 28—28, is a casting 29. The latter carries an electromagnet 30 located as clearly indicated in Fig. 5. The casting 29 is also provided with a relatively fixed jaw 31 having a semi-circular recess 32 within which is adapted to be received said pin 27. Pivotally mounted on the casting 29 20 is a second jaw member 33 having also a semi-circular recess 34 disposed opposite the recess 32 and adapted to engage said pin 27 on the top thereof. The jaw member 33 is pivoted as indicated at 35 and its inner end 25 is enlarged as indicated at 36, which portion 36 acts as an armature to the magnet 30. The armature 36 is provided with a laterally extending operating handle 37, the latter working in a suitable slot 38 in one of the side 30 walls of the casting 29. When the casting 29 is in its lowermost position, as indicated in full lines in Fig. 1^a, it is apparent that the relatively fixed jaw member 31 will engage the pin 27. If now the jaw member 33 is 35 moved by the handle 37, it also will engage the pin 27 and said jaw member will be held in its elevated position (shown in full lines in Fig. 5), by the magnet 30, assuming that the current is on. Hence it will be seen, that, 40 if the casting 29 is elevated, the test car A will also be elevated. This may be accomplished by any suitable means, but preferably I employ a plurality of sheaves 39 mounted on a cross shaft 40 carried by the 45 casting 29 and a plurality of sheaves 41 carried by a cross shaft 42 mounted on the top of the frame work. A cable 43 is run over said sheaves 39 and 41, the cable being passed around a floating pulley or wheel 44 near the 50 lower portion of the framework and finally on to a winding drum 45 which may be operated by a suitable motor 46, through proper reduction gearing 47. By winding up the cable 43, it is apparent that the casting 29, 55 together with the test car A, may be elevated to the position indicated by dotted lines in Figs. 1 and 1^a. If now the current is shut off from the electromagnet 30, it is apparent that the pivoted jaw member 33 will be released, thus disengaging the pin 27 and per-

mitting the car A to fall in the manner of a pendulum until it engages another car designated generally by the reference B. In order to cushion the movements of the pivoted jaw member 33 when the latter is released, I have provided a spring 48, the spring having a follower or cap 49 (see Fig. 5). By referring to Fig. 4, it will be seen that the cars A and B are each provided at their adjacent ends with a shock absorbing mechanism S and a dummy coupler C. When the cars A and B are in horizontal alignment, that is, when they first come together, the couplers C—C will be in alignment and engagement, as clearly indicated in Fig. 4. Each of the cars A and B is provided with an arm 50, one on one side and the other on the opposite side, said arms 50 being rigid with the respective cars by which they are carried. Each of said arms 50 is 85 adapted to engage a rod 51 attached to a reciprocating block or cross head which carries a pencil adapted to make a record on a revolving cylinder. The recording mechanism above referred to is merely indicated 90 diagrammatically inasmuch as I have fully described the same in my pending application 38,111 filed July 6, 1915 for improvement in means for recording actions of railway draft gears, and do not deem it necessary to enter into a detailed description 95 thereof in this application.

The recording mechanism above mentioned is adapted to make a record such as shown in said application 38,111 and said record may be read by means of the indicator described and claimed in my pending application 60687 filed November 10, 1915 for improvement in indicators. It is obvious that the recording device associated with the test car A will indicate the deceleration of the latter and the recording device associated with the car B will indicate the acceleration of the latter when the test car A impinges against the car B.

From the preceding description, it will be obvious that variations may be made in the weight of the test car and the height to which it is elevated, to thus simulate different conditions encountered in actual service. Knowing the weight of the falling mass and the distance through which it falls, it is obvious that the blow can be readily calculated. Knowing this, and having the record made when the cars come together, which shows the rates of deceleration and acceleration of the cars A and B respectively, the performance of the gears S, S which are being tested, can be determined.

I have herein shown and described what I now consider the preferred means of carrying out my invention, but the same is merely illustrative and I contemplate all changes and modifications that come within the scope of the claims appended hereto.

I claim:

1. In a testing mechanism of the character described, the combination with a framework, of means for normally swingingly supporting a car therefrom, said means being adjustable in length whereby the car may be lowered onto weighing scales, weighing scales associated with said framework by which said car may be weighed, and means for elevating said car while sustained by said supporting means.
2. In a testing mechanism of the character described, the combination with a swingingly mounted member arranged to carry at one end thereof a compressible gear to be tested, of a second member normally stationary and also arranged to carry at the end adjacent the first named member, another compressible gear, the second named member being mounted so as to permit acceleration thereof when struck by the first named member, and means for elevating and releasing the first named member from its elevated position to thereby permit it to fall under the influence of gravity and strike the second named member.
3. In a testing mechanism of the character described, the combination with a swingingly mounted car arranged to carry a gear at one end thereof, of a second car mounted on a track and also adapted to carry another gear at the end adjacent the first named gear, said second named car being free to move on said track when struck by the first named car, and means for raising the first named car to an elevated position and to release the same to thereby strike the second named car and accelerate the latter.
4. In a testing mechanism of the character described, the combination with a swingingly mounted member adapted to be loaded, of means for elevating said member, said means including a swingingly mounted element having a device thereon for temporarily clutching the swingingly mounted member, said device being releasable to thereby permit the swingingly mounted member to fall under the influence of gravity.
5. In a testing mechanism of the character described, the combination with a car swingingly carried by a plurality of supporting links, of means for elevating said car, said means including an element pivotally mounted similarly to the car, whereby both said element and the car swing always in horizontal alinement, said element being provided with devices for temporarily clutching a portion of the car while the latter is being elevated, said device being releasable to thereby permit the car to fall in the manner of a pendulum under the influence of gravity.
6. In a testing mechanism of the character described, the combination with a frame-work, of a plurality of links pivotally suspended from the top of said frame-work, a car pivotally supported from the bottom of said links whereby the car is adapted to swing always in a horizontal position, and means for elevating said car, said means including an element pivotally suspended from the top of said frame-work and arranged to swing in the same manner as said car, said element being provided with devices for temporarily clutching the car during the operation of elevating the latter.
7. In a testing mechanism of the character described, the combination with a track, a car on said track, the car being provided with a shock absorbing gear, a frame-work, a test car pivotally suspended from said frame-work and adapted to swing in a vertical plane in alinement with the car on the track and to impinge against the latter, said test car being provided also with a shock absorbing gear arranged to co-act with the gear on the first named car, and means for elevating the test car and releasing it so as to fall and impinge against the car on the track.
8. In a testing mechanism of the character described, the combination with a framework, of a plurality of links pivotally supported at their tops from said frame-work, a car supported from the bottoms of said links, the car being normally free to swing in the manner of a pendulum in a vertical plane, scales located at the bottom of said frame-work and normally out of engagement with said car, and means for lowering the car to engage said scales, whereby the weight of the car may be determined.
9. In a testing mechanism of the character described, the combination with a frame-work, of a car pivotally supported from said frame-work, scales located beneath the car but normally out of engagement therewith, means for lowering the car to thereby permit it to engage said scales, and means for elevating the car and release it from its elevated position.
10. In a testing mechanism of the character described, the combination with a frame-work, of a car pivotally supported from said frame-work, and means for elevating said car, said means including an element pivotally supported from the frame-work, said element being provided with a pair of jaws adapted to clutch a member on the car, an electromagnet carried by said element, one of said jaws co-acting with said electromagnet to maintain the jaws in closed position.
11. In a testing mechanism of the character described, the combination with a frame-work, of a car pivotally supported from said frame-work, and means for elevating said car, said means including an element pivotally supported from the frame-work,

said element being provided with a pair of jaws adapted to clutch a member on the car, an electromagnet carried by said element, one of said jaws co-acting with said electromagnet to maintain the jaws in closed position, and a winding drum and cable for elevating said element.

12. In a testing mechanism of the character described, the combination with a track, 10 of a car mounted on said track, said car having a gear at one end thereof, a framework, a second car pivotally supported from said framework and adapted to swing in a vertical plane in alinement with first named 15 car, the pivotally supported car being provided also with a gear at the end adjacent the car on the track, means for elevating the pivotally mounted car, and recording mechanism arranged to be actuated by portions 20 of said cars at the instant of impact one upon the other.

13. In a testing mechanism of the character described, the combination with a car mounted to swing in the manner of a pendulum and having a gear to be tested at one 25 end thereof, a second car normally stationary and located in the plane of movement of the swingingly mounted car and having also a gear to co-act with the gear on the swing- 30 ingly mounted car when the latter impinges against the normally stationary car, and means for recording the deceleration of one car and the acceleration of the other car when the two cars come together.

35 14. In a testing mechanism of the character described, the combination with a member pivotally mounted to swing in the manner of a pendulum in a vertical plane, said member being provided with a gear to be 40 tested, of a second member normally stationary, but adapted to be accelerated when given a blow by the swingingly mounted member, means for moving the swingingly

mounted member to an elevated position, and recording means arranged to be actuated at the instant of impact of the swingingly mounted member against the normally stationary member, said means recording the deceleration of the swingingly mounted member and the acceleration of the normally stationary member.

15. In a testing mechanism of the character described, the combination with a framework, of a car pivotally suspended from said framework, the car being adapted to receive loads of varying weight, a gear to be tested carried by said car, means for moving said car to an elevated position and releasing the same so as to fall under the influence of gravity, a second car mounted on a track 60 adjacent said framework and in the line of movement of the swingingly mounted car, and recording means arranged to be actuated at the instant of impact of the swingingly mounted car against the other car.

16. In a testing mechanism of the character described, the combination with a framework, of a car pivotally suspended from said framework, the car being adapted to receive loads of varying weight, a gear to be tested carried by said car, means for moving said car to an elevated position and releasing the same so as to fall under the influence of gravity, a second car mounted on a track 70 adjacent said framework and in the line of movement of the swingingly mounted car, and recording means arranged to be actuated at the instant of impact of the swingingly mounted car against the other car, and scales for weighing the swingingly mounted 75 car.

In witness that I claim the foregoing I have hereunto subscribed my name this 31st day of August, 1916.

JOHN F. O'CONNOR.
